TIRE

Raymond P. Hawkinson, Minneapolis, Minn., assignor to
Paul E. Hawkinson Company, Minneapolis, Minn., a
corporation of Minnesota

Filed Dec. 18, 1963, Ser. No. 77,852

Term of patent 14 years

(Cl. D90—20)

FIG. 1 is a fragmentary view in perspective of a tire embodying my new design, it being understood that the full line portions are repeated throughout the circumference of the tire by means of broken lines; and

FIG. 2 is a transverse sectional view thereof taken on the line 2—2 of FIG. 1.

The dominant features of my design reside in the portion shown in full lines.

The characteristic features of my design reside in the continuous zig-zag rib on the outer shoulders, having a lateral lug on the outer side of the rib only extending to the edge of the shoulder, in combination with the large and small cleats disposed within the outer V of the continuous rib as shown.

I claim:

The ornamental design for a tire, as shown and described.
